UNITED STATES PATENT OFFICE.

MARTIN SWINTEK, OF EDDYVILLE, IOWA.

HOISTING AND LOADING CONVEYER.

Application filed January 8, 1923. Serial No. 611,295.

To all whom it may concern:

Be it known that I, MARTIN SWINTEK, a citizen of the United States of America, and resident of Eddyville, Wapello County, 5 Iowa, have invented a new and useful Hoisting and Loading Conveyer, of which the following is a specification.

An object of this invention is to provide an improved construction for a hoisting and 10 loading conveyer mechanism.

A further object of this invention is to provide an improved single-cable, automatic-dump hoisting conveyer for use with 15 granular substances such as sand, gravel or shelled grain.

A further object of this invention is to provide improved means for mounting a 20 scoop or bucket to facilitate the operation of picking up, hoisting and depositing loose granular substance.

A further object of this invention is to provide improved means for automatically dumping the scoop or bucket when it has 25 reached a certain altitude.

A further object of this invention is to provide means for automatically inverting the scoop or bucket when it has been hoisted to a certain altitude, latching it in inverted 30 position during its descent, and automatically releasing it whereby it may assume the proper position for receiving another load when it has reached the bottom of the mechanism.

With these and other objects in view, my 35 invention consists in the construction, arrangement and combination of elements hereinafter set forth, pointed out in my claims and illustrated by the accompanying drawing, in which—

Figure 1 is a side elevation illustrating a 40 mechanism embodying my invention, the bucket being in position for loading. Figure 2 is an end view of the same. Figure 3 is a horizontal section on the line 3—3 of Figure 2. Figure 4 is an inner elevation, 45 partly in section, showing one of the tracks, the carriage and the scoop in position for dumping. Figure 5 is a similar view showing the carriage after it has started to descend, with the bucket latched in inverted 50 position.

In the construction of the mechanism as 55 shown a frame is provided which is rectangularly prismatic in form and composed primarily of corner posts 10, 11 connected

by side bars 12 and cross bars 13 and suitably braced. The frame may be of any suitable size and of any desired height to raise substance to the necessary elevation for depositing it as required for the particular 60 needs of the location. Opposed tracks 14, 15 are provided, arranged vertically and extending substantially from the bottom to the top of the frame and carried by the side bars 12. The tracks 14, 15 may be formed of 65

spaced bars as shown, or they may be composed of channel beams arranged with their channels opening inwardly toward each other, on opposite sides of the frame. A carriage, designated generally by the numeral 16, is 70 arranged transversely of the frame and is adapted for vertical sliding movement in the tracks 14, 15. In the event the tracks are formed of channel beams the carriage may be received bodily within the channels; 75

but in the present instance it is shown as having vertical tongues 16' projecting from its opposite sides between the spaced bars forming the tracks. Carried by one side of

the carriage 16, which will be considered the 80 rear side, are spaced bearings 17 carrying a horizontal rod or spindle 18. A scoop or bucket 19 is provided, having a substantially horizontal bottom and closed at its rear and sides but open at the opposite side 85 toward the carriage 16. Arms 20, 21 are

fixed rigidly to the sides of the scoop or bucket 19, near the rear wall thereof, and said arms are pivoted at their free ends on the rod or spindle 18. The arms are connected by cross bars 22 mounted between them and also by a rod 23 extending across 90

their outer or rear faces and projecting at its ends beyond said arms, rollers 24, 25 being journaled on the projecting ends of 95

said rod. A cable 26 is fixed at one end to the central portion of the rod 23 and is thus connected to the scoop, passes forwardly through an aperture in the carriage 16, engaging a direction pulley 27 journaled in 100

said aperture, thence upwardly through the top of the carriage. The cable 26 passes upwardly to the top of the frame and over a sheave 28 carried by said frame or by a bracket such as 29 rising above the frame. 105

The cable 26 then passes downwardly through the frame to the desired location for applying draft thereto, which may be by means of an engine and drum (not shown); and said cable may pass over an- 110

other direction pulley such as 30 located at or near the bottom of the frame and extend in any desired direction therefrom.

Side plates 31, 32 are carried by opposite sides of the frame at about the desired elevation for dumping the scoop or bucket 19, and a chute 33 extends downwardly and rearwardly from a point between said plates, projecting outside of the frame between the 10 posts 11 and extending to a suitable point of delivery, which may be to a car or wagon, or to a hopper communicating with sand and gravel washing and screening devices. Scoop dumping and inverting devices are 15 mounted on and carried by the inner faces of the plates 31, 32, one set of which is shown in Figures 4 and 5 as carried by plate 31, and it is to be understood that duplicates of such devices are mounted in opposed relation on the inner face of plate 32. The set of such devices shown will now be described in detail. A deflecting trigger 34 is pivoted at one end, by a bolt 35, to the plate 31, near the track 14, and the free end of said trigger 20 is beveled on its lower face and projects across the path of travel of the roller 24 on the scoop arm when said scoop is raised as hereinafter set forth. The trigger 34 is held in a position inclined upwardly toward the 25 track 14 by means of a stop pin 36 seated in the plate 31, and upward movement of said trigger is limited by a stop 37 carried by said plate near the pivot bolt 35. The upper 30 face of the trigger 34 serves as a track for the roller 24 at times, and a short track member 38 is rigidly mounted on the plate 31 in continuation of said trigger and also inclined downwardly away from the track 14. A longer track member 39 is fixed to the 35 plate 31 beneath the trigger 34 and track member 38 and is oppositely inclined. The track member 39 is spaced somewhat below the lower end of the short track member 38 at a point substantially above the upper end 40 of the chute 33, and thence extends inwardly and downwardly toward the vertical track 14, terminating at a point spaced somewhat from said vertical track. A vertical guide 45 is fixed to the plate 31 and extends downwardly in a substantially vertical plane from the lower end of the longer track member 39, a suitable distance.

In practical use, starting with the carriage and scoop or bucket in substantially the position shown in Figures 1 and 2, and assuming that a quantity of substance to be handled, such as sand, gravel, shelled corn or the like, is located within the lower end of the frame and between the lower ends of the vertical tracks 14, 15, draft is applied to the cable 26 in the manner provided. The first effect of such draft on the cable, through its connection to the scoop through the cross rod 23, is to pull said scoop toward the carriage 16, thus loading said scoop with a

quantity of the substance located at the lower end of the frame. In the loading operation the scoop arms 20, 21 gradually move to substantially vertical position, the carriage 16 moving upwardly in the tracks 14, 15 as said arms move through an arc, until the forward portion of the scoop is located beneath the carriage, in which position the arms 20, 21 are in contact with the carriage and the attached end of the cable 26 is located adjacent the direction pulley 27 in said carriage. Continued draft on the cable 26 will cause the carriage and scoop, with its load, to be raised, the carriage traveling upwardly in the vertical tracks 14, 15. The rollers 24, 25 pass upwardly between and adjacent the inner faces of the plates 31, 32 and as they contact the beveled inner ends of the deflecting triggers 34 said triggers are oscillated sufficiently to permit passage of said rollers, which when they have cleared permit the triggers to fall back to positions of rest on the stops 36. Thereafter draft on the cable 26 is released, as by unclutching the drum on which it is being wound, and the carriage and scoop, with its load, are permitted to descend by gravity until the rollers 24, 25 engage the upper surfaces of the deflecting triggers 34. Continued descent of the carriage causes the scoop 19 to be moved through an arc away from its depending position as the rollers 24, 25 travel downwardly and outwardly on the upper faces of the triggers 34 and thereafter on the short tracks 38. This causes the scoop 19 to be gradually moved to dumping position, with its open end downward over the upper end of the chute 33, into which the contents of the scoop are discharged. When the rollers 24, 25 reach the outer ends of the tracks 38 they drop off upon the longer tracks 39, the shock of such drop serving to dislodge any of the load which may have remained in the scoop, which is shown in this position in Figure 3. The bearings 17 and spindle 18 of the carriage have now passed below the horizontal plane of the rollers 24, 25, so that continued downward movement of the carriage causes a downward draft on the arms 20, 21, the rollers traveling downwardly and forwardly on the longer inclined tracks 39 until said arms have assumed substantially vertical position with the scoop uppermost and inverted. The scoop continues its descent in this position, being held temporarily by contact of the rollers with the vertical guides 40.

A latching device is provided for holding the scoop in its uppermost and inverted position throughout its descent, which is composed of latching arms 41, 42 spaced apart and arranged in horizontal position across the top of the carriage 16. The latching arms are formed with notches 43 on their

lower faces for engagement with one of the cross bars 22 connecting the scoop arms 20, 21, and are also beveled at their outer ends to facilitate engagement. At their opposite ends the latching arms 41, 42 are connected respectively to vertical bars 44, 45 which are arranged for vertical sliding movement in slide bearings formed in the forward face of the carriage 16, said sliding bars extending a material distance below said carriage and preferably being connected at their lower ends by a cross bar or brace 46. The sliding bars 44, 45 may be limited as to downward movement in the carriage by means of stop shoulders or lugs 47 adapted to engage the top of the carriage. The latching device is gravity operated and automatically engages the cross bar 22 when the arms are carried into vertical position, serving to hold the arms and scoop in this position until the carriage has descended to the bottom of the frame. Just before the carriage reaches the bottom the lower ends of the sliding bars 44, 45, or the cross-bar or brace 46 thereon, engage the ground surface, or the pile of sand or other substance thereon, stopping descent of the latching devices, and as the carriage and scoop continue to descend the latch arms are disengaged from the cross-bar 22 of the scoop arms and the scoop 19 is permitted to move through an arc, through force of gravity, to position for receiving another load: that is, to substantially the position of Figure 1. The sliding bars 44, 45 preferably are braced by a cross-bar 48 connecting them at their upper ends.

It will be observed that but a single cable is necessary for the operation of the device, that is to say the loading and hoisting cable 26; the operation of dumping the scoop being accomplished automatically upon release of the cable after the scoop has reached a certain elevation, and the scoop being automatically returned to position for loading upon reaching the bottom of the device.

I claim as my invention—

1. A mechanism of the class described, comprising a frame, a carriage mounted for vertical sliding movement in said frame, a scoop having rigid arms, said arms being pivoted to said carriage, a cable connected at one end to the scoop device, extending through said carriage and thence upwardly of said frame, draft on said cable being adapted first to swing said scoop toward the carriage for the purpose of loading it and then to move said carriage and the loaded scoop upwardly in the frame, and means for automatically dumping said scoop when it has reached a certain elevation in the frame.

2. A mechanism of the class described, comprising a frame, a carriage mounted for vertical sliding movement in said frame, a scoop pivoted to said carriage, a cable connected at one end to said scoop, extending

through said carriage and thence upwardly of the frame, draft on said cable being adapted first to swing said scoop toward the carriage for the purpose of loading it and then to move the carriage and loaded scoop upwardly in the frame, means for automatically inverting and dumping said scoop through release of draft on the cable after the carriage has reached a certain altitude. 75

3. A mechanism of the class described, comprising a frame, a carriage mounted for vertical sliding movement in said frame, a scoop pivoted to said carriage, a cable connected at one end to said scoop, extending through said carriage and thence upwardly of the frame, draft on said cable being adapted first to swing said scoop toward the carriage for the purpose of loading it and then to move the carriage and scoop upwardly in the frame, means for automatically inverting and dumping the scoop through release of draft on the cable after the carriage has reached a certain altitude, and means carried by said carriage for latching the scoop in inverted position during descent of the carriage. 85

4. A mechanism of the class described, comprising a frame, a carriage mounted for vertical sliding movement in said frame, a scoop pivoted to said carriage, a cable connected at one end to said scoop, extending through the carriage and thence upwardly of the frame, draft on said cable being adapted first to swing the scoop toward the carriage for the purpose of filling the same and then to move the carriage and loaded scoop upwardly in the frame, means for automatically inverting and dumping the scoop through release of draft on the cable after the carriage has reached a certain altitude, latching devices on the carriage for engaging and holding the scoop in inverted position during its descent, said latching devices being automatically released when the carriage reaches the bottom of the frame, whereby the scoop is permitted to drop to loading position. 105

5. A mechanism of the class described, comprising a frame, a carriage mounted for vertical sliding movement in said frame, a scoop pivoted to said carriage, a cable connected at one end to said scoop, extending through said carriage and thence upwardly of the frame, draft on said cable being adapted first to swing the scoop toward the carriage for the purpose of filling it and then to move the carriage and loaded scoop upwardly in the frame, means for automatically inverting and dumping the scoop through release of draft on the cable after the carriage has reached a certain altitude, latching devices slidably mounted in and extending below the carriage for engaging and holding the scoop in inverted position 120 125 130

during its descent, the projecting lower end of the latching devices being engaged when the carriage reaches the bottom of the frame, whereby the latching devices are released and the scoop permitted to move to loading position.

6. A mechanism of the class described, comprising a frame, a carriage mounted for vertical sliding movement in said frame, a scoop pivoted to said carriage, a cable connected at one end to said scoop, extending through said carriage and thence upwardly of the frame, draft on said cable being adapted first to swing the scoop toward the carriage for the purpose of loading it and then to move the carriage and loaded scoop upwardly in the frame, the scoop being formed with a laterally projecting member, a deflecting trigger pivoted on the frame and extending across the path of travel of said laterally projecting member and adapted to be oscillated thereby in upward movement of the scoop, said deflecting member being adapted to swing said laterally projecting member away from the carriage and dump the scoop when draft is released on the cable after said member has traveled above said deflecting member.

7. A mechanism of the class described, comprising a frame, a carriage mounted for vertical sliding movement in said frame, a scoop pivoted to said carriage, a cable connected at one end to said scoop, extending through said carriage and thence upwardly of the frame, draft on said cable being adapted first to swing the scoop toward the carriage for the purpose of loading it and then to move the carriage and loaded scoop upwardly in the frame, the scoop being formed with a laterally projecting member, a deflecting trigger pivoted on the frame and extending across the path of travel of said projecting member and adapted to be os-

cillated thereby in upward movement of the scoop, said deflecting trigger being adapted to swing said projecting member away from the carriage and dump the scoop when draft is released on the cable after said projecting member has traveled above said trigger, and track members on said frame adapted for engagement by said projecting member after it has left said trigger, whereby the scoop is inverted.

8. A mechanism of the class described, comprising a frame, a carriage mounted for vertical sliding movement in said frame, a scoop pivoted to said carriage, a cable connected at one end to said scoop, extending through said carriage and thence upwardly of said frame, draft on said cable being adapted first to swing the scoop toward the carriage for the purpose of loading it and then to move the carriage and loaded scoop upwardly in the frame, the scoop being formed with a laterally projecting member, a deflecting trigger pivoted on the frame and extending across the path of travel of said projecting member and adapted to be oscillated thereby in upward movement of the scoop, said deflecting trigger being adapted to swing said projecting member away from the carriage and dump the scoop when draft on said cable is released after said projecting member has traveled above said trigger, and track members on said frame adapted for engagement by said projecting member after it has left said trigger whereby the scoop is inverted, together with latching devices on said carriage adapted to engage and hold the scoop in inverted position during its descent.

Signed at Eddyville, in the county of Wapello and State of Iowa, this 19th day of December, 1922.

MARTIN SWINTEK.
